UNITED STATES PATENT OFFICE.

WILLIAM ANDERSON AND HENRY ANDERSON, OF EDINBURGH, SCOTLAND.

GLOBE-SUPPORT.

No. 905,128.

Specification of Letters Patent. Patented Dec. 4, 1908.

Application filed November 2, 1906. Serial No. 341,707.

To all whom it may concern:

Be it known that we, WILLIAM ANDERSON, a subject of the King of Great Britain and Ireland, residing at Edinburgh, Scotland, 5 (whose post-office address is Scotsman Arcade, North Bridge, Edinburgh,) and HENRY ANDERSON, a subject of the King of Great Britain and Ireland, residing at Edinburgh, Scotland, (whose post-office address 10 is Scotsman Arcade, North Bridge, Edinburgh,) have invented a certain new and useful Improvement in Globe-Supports, of which the following is a specification, reference being made therein to the accompanying drawings.

This invention relates to an appliance for carrying suspending globes for inverted incandescent gas, electric and other lamps, the objects being to provide elastic, self centering means for suspending globes so as to prevent them breaking when expanded by heat and of instantaneously detaching these when desired. And in order that our said invention and the manner of putting the same into 25 practice may be properly understood we have hereunto appended two explanatory sheets of drawings in which the same reference numerals are used to indicate corresponding parts in all the figures where shown.

30 Figure 1 is an external elevation looking in the direction of the arrow A (Fig. 2) of our globe suspender. Fig. 2 is a plan of Fig. 1 showing the spring clasp contracted to its greatest extent. Fig. 3 is a sectional elevation and Fig. 4 is a plan of same showing the spring clasp extended to receive the globe. Fig. 5 is a part sectional elevation showing an elastic self centering support and Fig. 6 is a face view of same. Fig. 7 is 35 a part sectional elevation showing an internal self centering support and Fig. 8 is a face view of same.

In carrying out our invention, as illustrated by Figs. 1 to 4 we use a spring clasp 40 in the form of two coils of suitable wire (preferably tempered steel) the inner coil 14 being of such a diameter as to firmly grip

the neck of the globe 15. The outer coil 16 which has a tendency to expand—the inner coil tending to contract—presses against the 50 sides of the gallery 17 for a certain distance around, its extremities being fixed at 18 thus insuring the centralizing of the inner or globe carrying coil 14, no matter how its diameter may be increased or reduced. The outer coil 55 16 is kept in position by means of guides 19. The inner or globe carrying coil 14 is supported by means of the projecting folds in the wire at 20, 21 and 22. The spring clasp may be extended by pressing the knobs 23 60 and 24 towards each other, or permitted to contract by releasing such knobs.

Figs. 5 and 6 show the self centering supports 19 forming part of the gallery and Figs. 7 and 8 show such supports attached to 65 the inside of the gallery. We are aware that elastic rings of spring wire have been used to suspend globes for gas, electric and other lamps and that these rings have been carried by supporting studs sliding in the gallery 70 and that spring holders have been used on gas burners for steadyng globes which are otherwise supported.

Having now described our invention what we claim as new and desire to secure by Letters Patent is;

In globe supports, the combination of a gallery with a self-centering spring clasp having an inner coil which grasps the neck of the globe and an outer coil whose ends 80 bear against the inside of the gallery, the outer coil having projecting supporting folds by which the clasp is expanded when said folds are pressed together and the inner coil having a projecting supporting fold which 85 acts as a guide as described.

In witness whereof we have hereunto set our hands in presence of two witnesses.

WILLIAM ANDERSON.
HENRY ANDERSON.
